UNITED STATES PATENT OFFICE.

JOHN B. CARY, OF BALTIMORE, MARYLAND, ASSIGNOR OF ONE-HALF TO
MARIE CLOTHILDE DELAVY, OF SAME PLACE.

ELECTRICAL COOKING APPARATUS.

SPECIFICATION forming part of Letters Patent No. 608,952, dated August 9, 1898.

Application filed March 14, 1898. Serial No. 673,755. (No model.)

To all whom it may concern:

Be it known that I, JOHN B. CARY, of the city of Baltimore and State of Maryland, have invented certain Improvements in Electrical Cooking Apparatus, of which the following is a specification.

In the description of the said invention which follows reference is made to the accompanying drawings, forming a part thereof, in

10 which—

Figure 1 is an exterior side view of the improved electrical cooking apparatus, showing the same as open or in condition for the reception of articles to be cooked. Fig. 2 is a plan of Fig. 1 with a part thereof removed. Fig. 3 is a cross-section of the apparatus when closed. Fig. 4 is a partly-sectional side view of the apparatus, showing the upper and lower sections thereof as extended or set farther 20 apart than in the preceding figures. Fig. 5 is a front view of Fig. 4. Fig. 6 illustrates a modification.

Referring now to Figs. 1, 2, and 3 of the drawings, A and B are metal boxes, of substantially the same size and shape, connected by strap-hinges C, four of which are employed, two of them being at the rear end of the boxes and the others at the sides of the same. The hinges are secured to the lower box A by screws

30 a. The members of the hinges above the lower box are slotted, the slots, which are denoted by b, extending to their ends, as shown in Figs. 1 and 2. The slotted portions of the strap-hinges are connected to the upper box B by means of screws c and thumb-nuts d, as shown in Fig. 1.

Within each box is a system of heating-wires D, of iron, in gangs, three of which are shown, and the three gangs are connected by 40 wires e, which run through eyes f at one end, and the other end of the gangs is united to the leading-wires g, which are of copper, and the whole is in an electric circuit. The wires D, having a greater resistance than the copper 45 leading-wires g, become heated by the electrical current, as is common in electric cooking apparatus.

Referring to Figs. 2 and 3, it will be seen that the wires D are electrically insulated and 50 tied together by means of insulating-strips E and the screws F.

G G are corrugated trays, of iron, with their adjoining faces covered with enamel or some other suitable hard smooth electricity-insulating material placed over the gangs of heated 55 wires and resting on the edges of the boxes A and B in such manner as to admit of their being slid from over the boxes to allow of access to the wires underneath in case of disarrangement or for cleaning purposes. 60

By reference to Figs. 1 and 2 it will be seen that the corrugated trays G extend beyond the fronts of the boxes A and B. The object of this arrangement is to allow of the placing of a pan H in such position with reference to 65 the boxes as to catch drippings of grease from their ends. The extension of the upper tray protects the lower one from the cooling effect of air and prevents the grease from hardening after it has passed from over the heating- 70 wires.

By corrugating the trays, as shown, the article to be cooked—for instance, a steak—is supported by heated surfaces, between which there is ample space for the passage of grease- 75 drippings from the meat, and the enameled surface does not burn into the meat, as would a metallic one, the heat being modified and more evenly distributed than if a good heat-conductor were employed. 80

By slotting the upper members of the strap-hinges and providing them with the thumb-nuts, as described, the boxes may be set apart to adapt the apparatus for the cooking of steaks which are thicker than the normal distance between the corrugated trays, as shown 85 in Fig. 3. This arrangement also admits of the separation of the boxes, as shown in Figs. 4 and 5, whereby the apparatus is adapted as a roaster, when a rectangular shield I is placed 90 between the trays to confine the heated air around the meat. This shield is provided with a revoluble shaft h, as shown in Fig. 4, whereby a joint or fowl may be suspended between the trays. One end of this shaft is 95 fitted with a handle j, whereby the article while roasting may be occasionally turned, so that all sides will be subjected to heat radiated from the trays.

In order that the roast may stand in any 100 position, the shaft is furnished with a notched wheel or disk J, and a spring-pawl K, fas-

tened to the end of the shield, rests on the circumference of the notched disk.

In Fig. 6 a series of ordinary incandescent lamps *M* are shown as substituted for the 5 heating-wires *D*.

I claim as my invention—

1. In an electrical cooking apparatus, the combination of two boxes each one having therein heating-wires and a corrugated tray 10 situated over the wires, and strap-hinges one member of the same being adjustably attached to a box whereby the boxes may be separated and held in a separated position, substantially as specified.

15 2. In an electrical cooking apparatus, the combination of two boxes having therein heating appliances, substantially as described, and a connecting-hinge one member of which is permanently secured to the lower box, and

the other member adjustably attached to the 20 upper box, whereby the said boxes may be separated and held in a separated position, substantially as specified.

3. In an electrical cooking apparatus, the combination of two boxes having therein heating appliances substantially as described, a connecting-hinge one member of which is permanently secured to one box and the other member adjustably attached to the other box, and a shield which is placed between the separated boxes to confine the heated air around the article being cooked, substantially as 25 30 specified.

JOHN B. CARY.
